UNITED STATES PATENT OFFICE

93,044

DESIGN FOR A TOOTHBRUSH

Frederic A. Parkhurst, Bethesda, Md., and William S. Elliot, Northampton, Mass., assignors to Pro-Phy-Lac-Tie Brush Company, Northampton, Mass., a corporation of Delaware

Application March 2, 1934, Serial No. 50,929

Term of patent 14 years

To all whom it may concern:

Be it known that we, FREDERIC A. PARKHURST and WILLIAM S. ELLIOT, both citizens of the United States of America, residing at Bethesda, county of Montgomery, State of Maryland, and Northampton, county of Hampshire, Commonwealth of Massachusetts, respectively, have invented a new, original, and ornamental Design for a Tooth Brush, of which the following is a specification, reference being had to the accompanying drawing forming a part thereof.

In the drawing:

Fig. 1 is a front elevation of the article showing our new design with the bristles omitted therefrom.

Fig. 2 is a side elevation,

Fig. 3 is a rear elevation,

Fig. 4 is a section along the line 4—4 of Fig. 1,

Fig. 5 is a section along the line 5—5 of Fig. 1, and

Fig. 6 is a section along the line 6—6 of Fig. 1.

The handle of the present design diverges gradually from the abbreviated neck portion adjacent the head to the outer or free end of the handle, which end is gracefully rounded or convexly curved. The side edges of the handle are straight and merge with the convex outer

end. In a vertical plane, the top and bottom faces of the handle converge or taper gradually toward the outer end so that the handle becomes gradually thinner from the neck portion toward the outer end (see Fig. 2). The entire handle from the head portion to the rear end has its opposite top and bottom faces gradually curved or rounded transversely to present convex portions or surfaces, the curvature of the faces being in proportion to the thickness of the handle. This is illustrated by the cross sectional views of Figs. 5 and 6. The side edges of the handle merge with the head portion and the junction is well defined by an abrupt sharp corner. The side edges of the head portion converge from the junction to the forward end of the handle and merge with the gracefully rounded or convex front end beyond the forward tuft of bristles. The top or outer face of the head portion is slightly and gracefully rounded transversely to present a smooth convex surface as shown in Fig. 4.

We claim:

The ornamental design for a tooth brush substantially as shown and described.

FREDERIC A. PARKHURST.

WILLIAM S. ELLIOT.
